UNITED STATES PATENT OFFICE.

ALBERT W. ENGEL, OF CHICAGO, ILLINOIS.

PICTURE-MOUNTING DEVICE.

Application filed May 22, 1922. Serial No. 562,609.

To all whom it may concern:

Be it known that I, ALBERT W. ENGEL, a citizen of the United States, residing in the city of Chicago, in the county of Cook and 5 the State of Illinois, have invented certain new and useful Improvements in Picture-Mounting Devices, of which the following is a specification, reference being had to the accompanying drawings, forming a part 10 thereof.

The purpose of this invention is to provide an improved device for securing photographs or other pictures and cards upon a mat, card, or other mount in a convenient 15 and ornamental manner, particularly if such pictures are provided with a margin or border of appreciable width. It consists in the features of construction shown and described, and as set forth in the claims.

20 In the drawings:—

Figure 1 is a face or plan view of a mounting device embodying this invention.

25 Figure 2 is a face view showing the device applied to one corner of a card or picture.

Figure 3 is a face view showing the device differently applied to one corner of a card or picture.

30 Figure 4 is a face view similar to Figure 1, showing a slightly modified form of the mounting device.

Like the picture mounting devices of my previous patents, such as Patent No. 1,386,-771, dated August 9, 1921, the present invention is in the nature of a corner fitting 35 of sheet material such as cloth or paper gummed on one surface and provided with a slit through which the corner of the card or picture is inserted in applying the 40 mounting device thereto, so that a part of the gummed area may be secured to the outer face of the card while the remaining area of the mounting device is secured to the mount itself. In the drawings, Figure 45 1 illustrates a corner fitting, A, of this nature which is of angular outline and is especially designed for use with pictures having either plain or ornamental marginal areas or borders of sufficient width to receive that portion of the mounting device 50 which is to be gummed to the surface of the picture without requiring this part of the device to overlap any of the picture area proper. For this purpose the angular outline of the fitting, A, includes a re-entrant angle formed between its adjacent sides, 1

and 2, and preferably a right angle, since nearly all pictures of angular outline are rectangular. The opposite outer sides or edges of the fitting, A, are designated at 3 60 and 4, respectively, and preferably also form a right angle so that when the device is applied as shown in Figure 2, said edges, 3 and 4, will coincide with the outer edges, B³ and B⁴, respectively of the picture card. 65

Preferably about midway between the inner and outer angular outlines the fitting, A, has a right angular slit composed of the main portions, 6 and 7, and transverse terminal portions, 8 and 9, communicating respectively with the main portions of the slits at their outer ends, that is, remote from the apex of their angle. When the fitting, A, is formed with rounded corners, 10, the terminal slits, 8 and 9, may connect 75 with the main slits, 6 and 7, in curves, 11, so that when the fitting is applied as shown in Figure 2, these curves, 11, become parts of the outline of the visible portion of the fitting. Figure 2 is intended to illustrate 80 a card or picture whose marginal area or border, B, is comparatively narrow, but still wide enough to accommodate that portion of the fitting, A, between its outer edges, 3 and 4, and the slit. Thus the area, C, of 85 the picture proper is not overlapped by the fitting, and the latter adds an ornamental touch to the border, B. The terminal slits, 8 and 9, extend outwardly from the main portions, 6 and 7, of the slit by exactly the 90 distance between said portions of the slit and the outer edges, 3 and 4, of the fitting; thus they serve to stop the fitting on the picture card with its outer edges, 3 and 4, registered directly over the edges of the 95 card. Obviously the fitting must have some material extending outwardly beyond the ends of the slits, 8 and 9, and this is furnished by tabs or lugs, 12, which thus project from the respective sides of the angular 100 outline.

When the border area is somewhat wider, as shown at D, in Figure 3, the fitting may be applied by inserting the corner of the card through the slit from the under or 105 gummed surface of the fitting, A, instead of in the manner indicated in Figure 2. This renders the area of the fitting between the slit and the re-entrant angle of its outline visible on the outer surface of the card, 110 while the remaining area adjacent the edges, 3 and 4, will lie under the card with

said edges registered with the edges, D³ and D⁴, respectively, which meet to form said corner. The visible portion of the fitting, A, thus adds an ornamental touch to the border, D, without overlapping the picture area, E, as seen in Figure 3.

Figure 4 illustrates a modified design, A¹, of the fitting in which the lugs or tabs, 15, are made with rectangular corners instead of 10 rounded, and in which the terminal slits, 8^a and 9^a, meet the main portions, 6^a and 7^a, of the slit sharply at right angles, as shown at 16. Consistently with this design, the corners, 17, are made rectangular instead of 15 rounded, as in Figure 1; but the use and operation of the fitting is exactly similar to that already described.

I claim:—

1. A picture mounting device consisting 20 of a corner fitting of sheet material gummed upon one surface for securement partly to one corner of the picture and partly to a mount therefor, and for that purpose having an angular slit with transverse terminal 25 portions extending away from the enclosed angle at the opposite ends of the slit respectively.

2. In a picture mounting device, as defined in claim 1, the angle of said slit being 30 a right angle.

3. In a picture mounting device as defined in claim 1, the angle of said slit being a right angle and its terminal portions extending respectively at right angles to the 35 main portions of the slit from which they lead.

4. A picture mounting device as defined in claim 1, having an outline which includes a re-entrant angle pointing into the angle of 40 the slit.

5. A picture mounting device as defined in claim 1, in which the outline of said fitting includes a re-entrant angle pointing into the angle of the slit, and the two sides forming said re-entrant angle are respectively 45 parallel to the main portions of said slit.

6. A picture mounting device as defined in claim 1, in which the angle of said slit is a right angle and the outline of the fitting includes two sides respectively parallel to 50 the main portions of said slit and meeting in a re-entrant angle which points into the angle of the slit.

7. In a picture mounting device as defined in claim 1, the angle of the slit being 55 a right angle and the fitting having a right-angled outline with tabs or lugs extending therefrom opposite the ends of said transverse terminal portions of the slit.

8. In combination with a rectangular 60 card or picture, a mounting device consisting of a corner fitting of sheet material gummed upon one surface for securement partly to the card and partly to the mount, said fitting having an outline which includes 65 two sides meeting at right angles to register with the corner outline of the card, being formed with a slit having outwardly extending terminal portions which lie respectively at right angles to the edges of the card 70 inserted in them, the fitting including tabs or lugs projecting respectively from its aforesaid sides beyond the ends of said terminal portions of the slit for securement to the mount.

In testimony whereof, I have hereunto set my hand at Chicago, Illinois, this 17th day of May, 1922.

ALBERT W. ENGEL.
